UNITED STATES PATENT OFFICE.

PATRICK H. TURLEY, OF HARRISBURG, PENNSYLVANIA, ASSIGNOR TO
ELLIOTT-FISHER COMPANY, OF NEW YORK, N. Y., A CORPORATION
OF DELAWARE.

REGISTER-SUPPORT FOR TYPE-WRITING AND ADDING MACHINES.

No. 820,838.

Specification of Letters Patent.

Patented May 15, 1906.

Application filed August 24, 1905. Serial No. 275,695.

To all whom it may concern:

Be it known that I, PATRICK H. TURLEY, a citizen of the United States, residing at Harrisburg, in the county of Dauphin and State of Pennsylvania, have invented a new and useful Register-Support for Type-Writing and Adding Machines, of which the following is a specification.

This invention relates to an adjustable support for the computing device or register of a combined type-writing and computing machine, the object being to provide the register guide-bar with supporting means involving provision for both the vertical and horizontal adjustment of the bar in order to secure an accurate adjustment of the computing device or register with respect to its actuating mechanism.

To the accomplishment of the object stated the preferred embodiment of the invention embraces one or more supporting-brackets adapted to be secured to the frame of the type-writing machine and including one or more vertically and horizontally adjustable posts carrying the register supporting or guiding bar and equipped with means for securely locking the parts against accidental movement after their adjustment has been effected.

In the accompanying drawings, Figure 1 is a perspective view of a portion of a type-writing-machine frame equipped with my register-support, the register being indicated in dotted lines. Fig. 2 is an end view of the support, and Fig. 3 is a sectional elevation thereof.

Each part is designated by its appropriate reference character in the several views.

It may be stated, by way of premise, that the Elliott-Fisher billing and adding machine of commerce includes an Elliott-Fisher billing or type-writing machine the carriage of which supports the operating mechanism of a computing device or register, which latter is mounted upon a supporting and guiding bar attached to the frame of the machine.

As the operating mechanism moves relative to the adding device or register as the carriage moves along the frame for letter-spacing, it follows that the adding device must be accurately positioned both horizontally and vertically in order to avoid interference of the parts. It is to secure this accurate location of the adding device in a machine of the

character stated that the present invention is designed.

In Fig. 1 of the drawings is shown a portion of the main frame 1 of an Elliott-Fisher billing-machine. To this frame is attached a pair of brackets 2, having attaching-lugs 3 imposed against and rigidly secured to the frame 1, as by screws 4 or other suitable securing means.

The upper end of each bracket 2 is provided with an opening 5, extending from front to rear, and at the bottom of the bracket is a clamp comprising a pair of rearwardly-extending lugs 6 and an adjusting-screw 7, connecting the lugs 6 at their rear ends. The aperture 5 at the upper end of the bracket is designed for the reception of a horizontal screw 8, provided with a vertically-apertured sleeve or head 9 at its rear end. The screw 8 also extends through a pair of clamping and adjusting nuts 10 and 11, which are opposed to the front and rear sides of the bracket 2.

Extending through each head or sleeve 9 is a supporting-post 12, having an enlarged upper end 13, a transversely-angular or flattened lower end 14, and an intermediate threaded portion 15. The enlarged upper end 13 of each post is screwed or otherwise secured to the under side of the register-supporting bar 16. The flattened lower end of the post is held between the clamping-lugs 6 of the bracket, and the threaded intermediate portion of the post is engaged by locking and adjusting nuts 17 and 18, bearing against the top and bottom faces of the sleeve or head 9, just as the nuts 10 and 11 bear against the opposite sides of the bracket 2.

In applying the register-supporting bar 16 to the frame 1 the brackets 2 are first screwed securely in place. The screws 8 are then passed through the brackets, the nuts 11 being first screwed thereon, and are secured by the nuts 10. The posts, first having the nuts 17 positioned thereon, are then passed through the heads or sleeves 9 and secured by the nuts 18, the lower ends of the posts being received between the clamping-lugs 6. The bar 16 is then screwed to the upper ends of the posts, as shown in Fig. 1, and the computing device or register R is slipped upon the bar 16 and secured in the usual manner. If the approximate adjustment of the parts obtained during the assembling thereof is found

not to be entirely accurate, the several nuts may be manipulated to throw the register up or down and forward or back to accurately position the same with reference to the actuating mechanism, which I have deemed it unnecessary to illustrate. Thus, if it is desired to elevate the register, the nuts 18 are screwed down away from the sleeves 9, and the nuts 17 are then turned to effect the elevation of the posts. The desired adjustment having been obtained, the nuts 18 are screwed back against the sleeve and the post is locked in position. In a similar manner the bar 16 may be dropped, it being simply necessary to rotate the nuts 17 in the proper direction to cause the posts to move downwardly, the nuts 18 being then screwed back, as before. If it is desired to adjust the register forward or back—that is to say, toward or from its actuating mechanism—the nuts 10 and 11 are manipulated in a manner similar to that just described in connection with the nuts 17 and 18, and the screw 8 is accordingly moved longitudinally in the desired direction to effect the lateral adjustment of the post 12. In order to secure great rigidity of the parts, as well as to prevent accidental turning of the post 12 or the screw 8, the clamp 6 is provided, the screw 7 being turned for the purpose of closing the clamp firmly upon the lower end of the post after the desired adjustment of the latter has been obtained.

It is thought that from the foregoing the construction and operation of my register-support will be clearly comprehended. It should be understood, however, that the invention is not limited to the structural details shown nor to the employment of a pair of brackets. Obviously, a single bracket might be employed and the register mounted directly thereon, or the bar 16 might be supported by a single bracket either in lieu of or in addition to the brackets shown. In short, I claim the right to effect any and all changes, modifications, and variations of the illustrated structure which may be fairly embraced within the scope of the protection prayed.

What I claim is—

50 1. The combination with a frame and a register-supporting bar, of an intermediate structure including means for adjusting the bar laterally, and separate means for adjusting the bar laterally in a direction substantially at right angles to the lateral adjustment first named.

2. The combination with a frame and a register-supporting bar, of two intermediate members movable together to adjust the bar laterally in one direction, and relatively inmovable to effect the lateral adjustment of the bar in another direction.

3. The combination with a frame, of a register-supporting bar, and separate supports for the opposite ends of the bar, each support

including two members adjustable in unison to adjust the bar laterally in one direction and relatively adjustable to adjust the bar laterally in another direction.

4. The combination with a frame, of a register-support including a bracket secured to the frame, a horizontally-adjustable member carried by the bracket, means for adjusting and locking said member, a post carried by the horizontally-adjustable member, and means for vertically adjusting and locking said post. 70

5. The combination with a frame, of a register-support including a bracket secured to the frame, a horizontally-disposed screw passed through the bracket and having an apertured head, adjusting and locking nuts cooperating with the screw, a threaded post passed through the apertured head of the horizontal screw, and adjusting and locking nuts cooperating with said post. 75

6. The combination with a frame, of register-supporting means including a bracket secured to the frame and provided with a clamp, a horizontally-adjustable member carried by the bracket, and a vertically-adjustable post carried by said member and disposed to be engaged and held by the clamp. 80

7. The combination with a frame, of a register-supporting bar, and a plurality of supporting devices for said bar, each of said devices including a bracket secured to the frame, a horizontally-adjustable screw carried by the bracket, nuts for adjusting and locking said screw, a vertically-adjustable post carried by the screw, locking and adjusting nuts cooperating with the post, and a clamp carried by the bracket and engaging the post. 90

8. The combination with a frame, of a register-support including a horizontally adjustable screw, a vertically-adjustable post carried thereby, and means for preventing turning of the screw or post. 95

9. The combination with a frame, of horizontally-adjustable members carried by the frame, posts carried by said members and vertically adjustable relative thereto, and a horizontally-disposed register-supporting bar carried by the upper ends of the posts. 100

10. The combination with a frame, of a supporting member horizontally adjustable thereon, a second supporting member carried by and adjustable with the member first named and also having independent vertical adjustment, and a register-supporting bar disposed over and supported by the vertically-adjustable member, whereby said bar may be shifted horizontally by the adjustment of one member and vertically by the adjustment of the other member. 110

11. Register-supporting means including a bracket, a member horizontally adjustable on the bracket, means for locking said member in its adjusted positions, a second mem- 115

ber vertically adjustable on the member first named, means for securing the second member in its vertically-adjusted positions, and a horizontal register-supporting bar adjustable with the second member.

12. A register-support including a rigid member, a horizontally-adjustable screw carried thereby, a nut retaining the screw, a threaded post extended through the head of the screw, a nut retaining the post, and a register-supporting bar resting on the post.

13. Register-supporting means including

a rigid member, a horizontally-adjustable screw carried thereby, a vertically-adjustable threaded post extended through the head of the screw, and a clamp engaging the lower end of the post.

In testimony that I claim the foregoing as my own I have hereto affixed my signature in the presence of two witnesses.
